Attorney.

UNITED STATES PATENT OFFICE.

ARTHUR LINDNER, OF RICHMOND, INDIANA, ASSIGNOR OF ONE-HALF TO FRED D. BETHARD, OF RICHMOND, INDIANA.

FEED-SCREW-ADJUSTING MECHANISM.

1,239,193.

Specification of Letters Patent.

Patented Sept. 4, 1917.

Application filed August 7, 1916. Serial No. 113,447.

To all whom it may concern:

Be it known that I, ARTHUR LINDNER, a citizen of the United States, residing in the city of Richmond, in the county of Wayne and State of Indiana, have invented a new and useful Feed-Screw-Adjusting Mechanism, of which the following is a full, clear, and comprehensive specification, being such as will enable others to construct and use the same with exactitude.

The object of this invention, broadly speaking, is to provide a machine element which will be positive in action, strong and durable in construction, easily operated and controlled, and which can be manufactured and installed at a comparatively low price.

More specifically stated my object is to provide a feed-screw adjusting mechanism which will eliminate the end play of the screw, which will enable one to obtain absolute accuracy in the work performed thereby, and which is adapted to compensate for the wear incident to usage.

Other minor objects and particular advantages of the invention will be brought out in the course of the following description, and that which is new will be correlated in the appended claims.

The preferred means for carrying out the principles of my invention in a practical manner is shown in the accompanying drawings, in which—Figure 1 shows my invention in elevation, certain parts thereof being in vertical section, and showing the same assembled in operative condition.

Fig. 2 is a right-hand side elevation of the invention.

Fig. 3 is a detail view showing a side elevation of the hanger or boss as stripped of the removable parts.

Fig. 4 is an outer face view of the right-hand nut alone. And

Fig. 5 is an outer face view of the left-hand nut alone.

Similar indices denote like parts throughout the several views.

In order that the construction, the advantages, and the operation of my invention may be better understood and appreciated I will now take up a detailed description thereof in which I will set forth the invention as fully and as comprehensively as I may.

In the drawings letter A denotes a fixed

element, such as the body or frame of a machine.

Extending from the element A is the hanger or boss B, through the central portion of which is formed a large round aperture C, the interior of said aperture being smooth or unthreaded.

Also formed through the hanger B are the three smooth bore small apertures D, E and F, which are spaced an equal distance apart around and concentric with the aperture C.

The screws 1, 2 and 3 are adapted to snugly fit and slide in the respective apertures D, E and F, extending parallel with the screw-shaft 4. The said screw-shaft extends through the aperture C but not in contact with the hanger or boss B.

Numeral 5 denotes the face nut, which is preferably round or disk-shape, and it has a central aperture G therethrough which is interiorly threaded to correspond with and engage the threads of the shaft 4 on which it is adapted to be run. Also formed through the nut 5 are the smooth bore or unthreaded apertures H, I and J which are spaced an equal distance apart around and concentric with the aperture G, and they register with the respective apertures D, E and F. The screws 1, 2 and 3 are adapted to snugly fit and slide in the respective apertures H, I and J.

Letters K, L and M denote threaded apertures, formed through the nut 5, and alternating with the apertures H, I and J, and they are also concentric with the aperture G.

Numerals 6, 7 and 8 denote the three set screws which are threaded into the respective apertures K, L and M, and they extend parallel with the screws 1, 2 and 3.

Numeral 9 denotes the back nut, which is of the same size as the nut 5, and it has a threaded central aperture N therethrough into which the shaft 4 is adapted to turn. The nut 9 has three apertures O, P and Q therethrough which register with the apertures D, E and F, respectively, and also with the respective apertures H, I and J, and into which the threaded portions of the respective screws 1, 2 and 3 are inserted.

The screw 4 may be revolved in any well known manner incident to machine tools, such for instance as grinding machines, for

the purpose of making adjustments and feeding the work or the tool in relation to the work to be performed, in which case the element A would be a part of the body of the machine, while the part B would project therefrom, being either integral therewith or attached thereto as preferred.

After placing the screw 4 through the aperture C the nuts 5 and 9 are run onto the screw until they are near the hanger B and located on each side thereof as shown.

The screws 1, 2 and 3, are then inserted through the apertures H, I and J, then through the apertures D, E and F, and then 15 screwed into the apertures O, P and Q, with the heads of the screws contacting with the face of the nut 5, and the nut 9 contacting with the side of the hanger B, and with the nut 5 spaced from the hanger B, substantially as shown in Fig. 1.

It is now evident that by further tightening the said screws that the nut 5 will be forced toward the hanger B until the end play of the screw is taken up or eliminated, 25 by which it is evident that the screw 4 may be made as tight as desired, in order to provide a fine adjustment.

After the above it is evident that the set-screws 6, 7 and 8, should be run into the 30 apertures K, L and M until their points contact securely with the face of the hanger B which, manifestly, will secure the parts in their adjusted positions, but permitting the screw 4 to revolve and travel to the right and 35 the left, but without lost motion or end play.

Should the threads of the screw or the nuts wear to any appreciable extent then one has only to first loosen the set-screws 40 and then tighten the screws 1, 2 and 3, thereby bringing the nuts toward each other and thereby taking up all wear of the threads, after which the set-screws are again tightened which will again place the feed-screw 45 in perfect adjustment.

I desire that it be understood that various changes may be made in the several details of construction and arrangement without departing from the spirit of my invention 50 and without sacrificing any of the advantages thereof.

Having now fully shown and described my invention, what I claim and desire to secure by Letters Patent of the United 55 States, is—

1. A. feed-screw adjusting mechanism comprising, in combination with a fixed hanger having a central smooth aperture therethrough, a feed-screw disposed loosely through said aperture and without contact with the hanger, a face nut located on one 60 side of the hanger and normally spaced

therefrom, a back nut located on the other side of the hanger and normally in contact with the hanger, the feed-screw being 65 threaded through both of said nuts, a plurality of screws extending loosely through smooth apertures in the face-nut and the hanger with their heads contacting with the outer face of the face nut and with the other 70 end portions of said screws threaded through apertures in the back nut, a set-screw located between each two of the main screws and located parallel therewith, the same being threaded through the face nut 75 with their points contacting with the hanger whereby the nuts and the feed-screw are prevented from vibrating with relation to the hanger and by which back-lash is prevented with relation to the feed-screw, all 80 substantially as shown and described.

2. A feed-screw adjusting mechanism, in combination with a hanger having a central aperture therethrough, a feed-screw disposed loosely through said aperture, a face 85 nut located on one side of the hanger, a back nut located on the other side of the hanger, both of said nuts being threaded onto the feed-screw, screws extending in an axial direction through both of said nuts and the 90 hanger and adapted to draw the nuts toward each other, and set-screws extending through one of said nuts and adapted to contact with the hanger to secure the parts in adjusted position, all substantially as set forth. 95

3. A feed-screw adjusting mechanism, comprising in combination with a hanger having a central aperture therethrough, a feed-screw disposed loosely through said aperture, a face nut located on one side of 100 the hanger, a back nut located on the other side of the hanger, the feed-screw being threaded through both of said nuts, a plurality of screws extending loosely through smooth apertures in the face nut with their 105 heads contacting with the face of the face nut and then extending loosely through smooth apertures in the hanger and with the other end portions of the said screws threaded through apertures in the back nut, and a plurality of set-screws extending through threaded apertures in the face nut with their points adapted to contact with the hanger in order to clamp the back nut against the hanger, all substantially as 110 shown and described and for the purposes set forth.

In testimony whereof I have hereunto subscribed my name to this specification in the presence of two subscribing witnesses.

ARTHUR LINDNER.
